UNITED STATES PATENT OFFICE

2,025,572

ELECTROHYDRAULIC PRESSURE OPERATING MECHANISM

Robert H. Collingham, Rugby, England, assignor to General Electric Company, a corporation of New York

Application January 20, 1934, Serial No. 707,619
In Great Britain March 7, 1933

2 Claims. (Cl. 60—52)

This invention relates to improvements in electrohydraulic pressure operating mechanism and has for its object to produce an hydraulic operator to take the place of large alternating or direct current magnets and solenoids and to replace air cylinders where quiet and smooth thrust is desired through a given distance.

The present invention consists in a device for applying pressure comprising a liquid container having a casing mounted within it divided into two portions, one of which forms the cylinder of an hydraulic motor, and the other contains an impeller which is driven by means of an electric motor and causes a differential pressure between the two sides of a movable vane contained in the operating cylinder. The impeller is driven by electric means which can be automatically operated if so desired. The interior of the casing is filled with liquid.

The invention will be better understood from the following description considered in connection with the accompanying drawing, in which Fig. 1 represents a vertical cross-section of the hydraulic operator, Fig. 2 represents a transverse section through the operating cylinder on the line 2—2 of Fig. 1 and Fig. 3 is a horizontal section taken on the line 3—3 of Fig. 1, viewed in the direction of the arrows. In Fig. 1, a driving means 10, preferably an electric motor, rotates shaft 11 to which is secured an impeller 12. Impeller 12 rotates in a casing of which parts 13 and 14 form the walls thereof. Part 13 also forms the bottom wall of the cylindrical chamber defined by cylinder wall 15 which contains the vane 16 on which the differential pressure is exerted. An external container 17 surrounding cylinder 15 and spaced therefrom, is filled with fluid up to the line indicated.

Referring to Fig. 2, the cylindrical chamber defined by cylinder wall 15 contains the movable vane 16 which is mounted on a sleeve 18 through which the impeller shaft 11 passes. Cylinder 15 also contains a fixed abutment 20. The upper end of the sleeve 18 is attached to a lever 21 which is suitably keyed thereto.

The operation of the device is as follows:

When the motor 10 is energized, shaft 11 rotates and drives the impeller 12 thus causing centrifugal pressure to be created in the chamber formed between the parts 13 and 14. This pressure is transmitted through aperture 22 to the inside of chamber 15 where it acts on the movable vane 16. The interior of the chamber on the other side of the movable vane 16 is connected by means of an aperture 25 to fluid at atmospheric pressure. The result is that, due to the pressure difference on opposite sides of the vane 16, the latter is rotated in a clockwise di-

rection looking at Fig. 2, and consequently the lever 21 is rotated due to the fact that it is keyed to the sleeve 18. The other end of the lever 21 is connected by suitable linkage to operate the means for which the thrust provided by the lever 21 is required. As soon as the motor 10 is deenergized, the lever 21, sleeve 18, and vane 16 are returned to the initial or off position by means of a helical spring 24 which is attached to lever 21 and the casting which forms a support for motor 10.

Due to the fact that all the parts are submerged in fluid and that as quickly as the fluid enters aperture 22 fluid is also discharged in an equal quantity through aperture 25, the fluid in the container 17 remains at a constant level. Furthermore, when the fluid is discharged through aperture 22 due to the fact that the vane 16 is being returned to its off position by the spiral spring 24, the dash-pot effect is obtained which prevents hammering and allows the vane 16 to return to the off position quietly.

This apparatus can be applied to a large variety of purposes, such as opening and closing down, operating signals, clutches or feed and reversing mechanism of large machine tools.

What I claim as new and desire to secure by Letters Patent of the United States, is:

1. A pressure applying device comprising a liquid container having a cylinder mounted within it, said cylinder being divided into two portions, a rotatably mounted shaft concentric with the axis of said cylinder, an impeller mounted on said shaft in one of said portions, a sleeve in the other of said portions surrounding said shaft, a rotatable vane mounted on said sleeve, and means whereby the pressure produced by the rotation of said impeller is transferred to one side of said vane so as to cause an unbalance of pressure on opposite sides of said vane to effect operation thereof.

2. An hydraulic operating mechanism comprising a liquid container, a two part cylinder mounted within said container, a rotatable drive shaft mounted concentrically with the axis of said cylinder, a rotatable sleeve surrounding said shaft, a rotatable vane in one of the parts of said cylinder mounted on said sleeve, a rotary impeller in the other part of said cylinder mounted on said shaft, an electric motor for rotating said shaft, means whereby the pressure created by the rotation of said impeller is transferred to one side of said vane so as to cause an unbalance of pressure on the opposite sides of said vane to effect rotation thereof, and a lever connected to said sleeve whereby force is transmitted to the device which it is to be applied.

ROBERT H. COLLINGHAM.
